CONTAINER CLOSURE

Adolf Zimmerli, Zurich, Switzerland

Application November 12, 1957, Serial No. 695,751

3 Claims. (Cl. 222—541)

The present invention relates to a closure for containers such as collapsible tubes, bottles, cans, etc. which unlike the conventional screw cap closures can be opened without removing the closure or any part thereof which is required for closing the container again.

Container closures of this kind are known which comprise a base member through which a passage is provided, a shutter provided with an opening and slidably supported and guided on the base member so as to permit said opening to be brought into and out of alignment with said passage in the base member, and a cap mounted on said base member for rotation substantially about the axis of said passage, said cap overlapping said shutter for retaining it on said base member and having an axial opening which remains in alignment with said passage regardless of the angular position of the cap about its said axis. This cap is coupled with the shutter in such a manner that the opening of the latter can be moved into and out of alignment with the passage in the base member and the axial opening in the cap by rotating the cap about its said axis.

On the other hand, container closures are known the discharge opening of the base member of which is hermetically sealed by a diaphragm which on opening the closure for the first time is pierced, torn, cut out or otherwise disrupted by appropriate means.

In a container closure of the above-mentioned type, such a diaphragm would not be readily accessible because it would be necessary first to move the shutter into the "open" position and then to disrupt the diaphragm by means of a separate instrument which would have to be introduced through the aligned openings of the shutter and cap.

One object of the present invention is to provide a container closure of the aforesaid type which is secured against inadvertent opening before it is to be opened for the first time.

A further object of the invention is to provide in a container closure of the said type a disruptable part which hermetically seals the passage in the base member before the container closure is opened for the first time, and means whereby said disruptable part can be disrupted and removed without resorting to a separate instrument.

Still another object of the invention is to provide means whereby before the closure is to be opened for the first time the opening of the cap is substantially closed so that no dust or dirt can be deposited in that opening or reach the shutter; thereby, such dust or dirt will not contaminate the container contents discharged through that opening after the closure is first opened nor could it interfere with the motion of the shutter and cap.

These and other objects are fulfilled according to the present invention by providing in the base member of a container closure of the aforesaid type, a blind passage extending into said base member from the inner side thereof, said blind passage and the outer surface of the base member defining between them a disruptable integral portion of said base member, said disruptable portion

2

comprising a plug which extends outwardly through said openings of said shutter and said cap, with said shutter maintained in a position in which its opening is in alignment with the opening of the cap and with the disruptable portion of the base member overlying the blind passage.

By extracting said plug, said disruptable portion of the base member will be disrupted and the blind passage opened through the base member. Simultaneously, the openings of the shutter and cap will be opened by the removal of the plug therefrom, but the shutter will become free to slide out of alignment with the formerly blind passage and with the opening in the cap for closing said passage.

In order to facilitate a fuller understanding of the invention, specific embodiments thereof will be described hereinafter, by way of example only and with reference to the accompanying drawing in which:

Fig. 1 shows a closure for a collapsible tube, in the condition before it has been opened for the first time, with the shutter and cap shown in section along the line I—I of Fig. 5.

Fig. 2 shows the same closure in open condition with the disruptable portion of the base member removed, the shutter and cap being again shown in section along the said line I—I.

Fig. 3 is a similar partly sectional view of the closure with the shutter and cap in a position halfway between their open position as shown in Fig. 2 and their closed position.

Fig. 4 is a similar view, partly in section along the said line I—I, with the shutter and cap in their closed position.

Fig. 5 is a view of the closure with the cap removed, as seen in direction of the arrow V in Fig. 1, with the shutter in the same position as in that Fig. 1.

Fig. 6 is a similar view, with the cap removed and as seen in the direction of the axis of rotation of the shutter, of an alternative embodiment of the invention.

Fig. 7 is a partly sectional view of the alternative embodiment of the closure shown in Fig. 6, in the condition before it has been opened for the first time, showing the section of the shutter indicated by line VII—VII of Fig. 6 aligned with the section indicated by line VIII—VIII of the base member.

Fig. 8 is a similar partly sectional view of the alternative embodiment of the closure, with the shutter and cap in their closed position, both the shutter and the base member being shown in section along the line VIII—VIII of Fig. 6.

Fig. 9 is another similar partly sectional view of the alternative embodiment of the closure, with the shutter and cap in their dispensing position, showing the section of the shutter indicated by line IX—IX of Fig. 6 aligned with section VIII—VIII of the base member.

The tube closure shown in Figs. 1 to 5 comprises a base piece 1 which by means of an internal thread 2 is tightly screwed onto a threaded socket 4 provided at the upper part of a collapsible tube 3. Alternatively, the base piece 1 could be integral with the cover part 4a of the collapsible tube. The base piece 1 in its lower part has a cylindrical surface 5 and above the latter a spherical surface 6 of a somewhat smaller diameter than the cylindrical surface 5, so that above the latter an annular shoulder 7 is provided in a plane perpendicular to the axis of the base piece. The spherical surface 6 extends up to an inclined plane shoulder 8, above which the head piece has an upper spherical surface 9 which is concentric to the lower one 6 but has a somewhat smaller radius than it. An initially blind passage 10 which continues the passage 11 of the threaded socket 4 extends axially into the base piece 1 up to a very small distance from the upper spherical surface 9. In axial alignment with this blind passage 10, an integral plug 28 rises above

the upper spherical surface 9. The diameter of that plug 28 at its root is slightly less than that of the passage 10 at its blind end, so that the plug is connected to the remainder of the base piece 1 by a narrow annular zone of material between the blind end of the passage 10 and the spherical surface 9. The thickness of the material in that annular zone is such that it can be disrupted and the plug 28 torn away from the remainder of the base piece 1, by application of manual force to the plug 28.

On the spherical surface 9 a shutter 13 in the general shape of a calotte-shaped shell is seated. Its outer surface 14 is spherical and has the same radius and the same center as the lower spherical surface 6 of the base piece 1. The edge of the shutter rests on the whole surface of the inclined upper shoulder 8, and the shutter would be rotatable about an axis perpendicular to that shoulder but for the fact that the aforementioned plug 28 extends through an opening 27 of the shutter.

The shutter 13 is retained on the base piece 1 by a cap 15, the inner surface of which fits over the outer surface 14 of the shutter 13 and over the lower spherical surface 6, the surface of the lower shoulder 7 and the cylindrical surface 5 of the base piece. At its lower edge, the cap 15 has an inner flange 16 which engages a groove 17 of the base piece 1 and thus retains the cap 15 on the shutter 13 and on the base piece 1. In order that the cap may be slid onto the base piece 1 in assembling the closure, its skirt overlying the cylindrical surface 5 of the base piece 1 is provided with radial slots 18, so that it can be expanded and the segments of the flange 16 which are separated from each other by these slots can slide over the surface 5 of the base piece until they snap into the groove 17. The outer surface of the cap 15 is provided in its lower part with corrugations or ribs 19, by means of which the cap can be gripped. In axial alignment with the blind passage 10 of the base piece, the cap has a circular opening 20 through which the plug 28 extends outwardly.

In its inner wall surface, the cap has a groove 21, the center line of which is in an axial plane and which is engaged by an integral lug 22 projecting above the spherical outer surface 14 of the shutter 13. The axis of the lug 22 intersects the axis of the base piece at the common center of its spherical surfaces 6 and 9 and of the outer surface 14 of the shutter 13. When plug 28 has been removed as shown in Fig. 2 and the cap 15 is rotated about the axis of the base piece, the cap 15 therefore takes the shutter 13 along with it. This shutter then rotates along the shoulder 8 about an axis which intersects the axis of rotation of the cap at the said center, the lug 22 always engaging the groove 21 in a radial direction without ever jamming in it. Fig. 3 shows the cap 15 and the shutter 13 in their angular positions about their axes in which the center line of the groove 21 and the axis of the lug 22 are in the plane of the drawing, which is the plane passing through the axes of both members 13 and 15. The lug 22 then engages the groove 21 at the lower end thereof. However, the position shown in Figs. 1 and 5 in which the plug 28 retains the shutter 13 is at right angles in anti-clockwise direction (as seen in the direction of the arrow V of Fig. 1) and the corresponding position of cap 15 is at about 70° in anticlockwise direction (as seen axially from above in Fig. 1) from the position shown in Fig. 3; the lug 22 then is in the position shown at 22', at the upper end of groove 21. After the plug 28 has been removed (see Fig. 2), the shutter 13 can be rotated through 180° about its own axis of rotation, by rotating the cap 15 some 140° in clockwise direction to reach the closed position shown in Fig. 4, in which the lug 22 is again at the upper end of groove 21, in the position 22''. In each of these positions 22' and 22'', the lug abuts the upper end of the groove 21 and prevents further rotation of the cap 15 and of the shutter 13.

At that place of its outer surface 14 which is beneath

the opening 20 of the cap in the closed position shown in Fig. 4, the shutter has a bulge 23 rising above the remaining spherical part of that outer surface. Opposite this bulge, the inner surface of the shutter has a circular recess of larger diameter than the bulge, so that the annular portion 25 of the wall of the shutter surrounding the bulge is thin and resilient and the portion of the shutter wall comprising the bulge can be moved inwards by pressure on the bulge.

When the shutter 13 is in the position according to Fig. 4, the resilient portion 25 of the shutter wall contacts the cap 15 around the opening 20, and the bulge 23 projects into the opening 20, thus retaining the shutter in the closed position of Fig. 4 against inadvertent rotation towards the open position shown in Fig. 2.

When the shutter 13 is rotated out of the position according to Fig. 4 by means of the cap 15, the bulge 23 is displaced from the region of the opening 20 and engaged beneath the wall of the cap, thus being depressed inwardly while the resilient portion 25 of the shutter wall is deformed as shown in Fig. 1.

In the alternative embodiment shown in Figs. 6 to 9, which represents a closure for a container for liquids, the shutter has a small discharge opening 29 and a larger refill opening 27, the latter being the opening through which the plug 28 extends before the closure is opened. In this embodiment, the openings 27 and 29 and the depressible bulge 23 which is to engage the central opening of the cap 15 in the closed position, are in radial planes of the shutter which are at 120° of each other and the lug 22 is in the radial plane opposite that of the bulge 23. The groove 21 of the cap in which the lug 22 of the shutter is slidably in this instance extends somewhat higher up towards the central opening of the cap, so as to permit the shutter to be rotated through 120° in either direction from its position shown in Figs. 6 and 8, in which the lug 22 is in its lowermost position as in Fig. 3. Such rotation of the shutter through 120° about its oblique axis corresponds to a rotation of the cap (not shown in Fig. 6) through about 90° about the axis of the closure.

Before the closure is unsealed the shutter 13 is in an angular position on the base piece 1 in which the refill opening 27 is in alignment with the blind passage 10 of the base piece, and the plug 28 of the latter extends through that refill opening as shown in Fig. 7, as long as the closure is to remain sealed. The lug 22 then is in the position shown at 22' in Figs. 6 and 7, and at the upper end of the cap groove 21. For unsealing the closure, the plug 28 is torn off as in the former example, so that the refill opening 27 of the shutter 13 establishes an open communication between the passage 10 and the outside, through the central opening 20 of the cap 15 as shown in Fig. 2 for the first embodiment. The closure then can be closed by anti-clockwise rotation of the cap through 90°, whereby the shutter 13 is similarly rotated through 120° into the position of Figs. 6 and 8, in which the shutter opening 27 is between an unpierced portion of the spherical surface 9 of the base piece 1, and the solid wall of the cap 15, while the bulge 23 of the shutter is in alignment with the passage 10 and engages the central opening 20 of the cap 15 as shown in Fig. 4 for the formerly described embodiment. By rotating the cap and shutter further anti-clockwise through a similar angle of 90° for the cap and 120° for the shutter, into the position shown in Fig. 9, whereby the lug 22 is carried into position 22'' and again abuts the upper end of the groove 21, the small discharge opening 29 of the shutter is brought into alignment with the passage 10 and the cap opening 20.

It is then possible to eject liquid from the container 3 by exerting a pressure on the latter or by shaking it.

After use, the cap 15 is again rotated into the position according to Figs. 6 and 8, whereby the bulge 23 snaps

into the cap opening 20 and prevents unintentional opening of the closure, by opposing rotation of the cap 15 out of that position or beyond that position.

The parts of the closure preferably are made from a tough, resilient synthetic resin such as polyethylene. It is then unnecessary to produce the thread 2 of the base piece in the manufacture of that piece, that thread being automatically obtained by screwing the piece onto the threaded socket 4 of the collapsible tube.

Alternatively, the base piece 1 could be permanently connected to the collapsible tube, for instance by glueing, by welding, or the like. In place of the internal thread 2, the base piece and the tube socket then may have smooth e.g. conical, fitting surfaces at which they are connected. As already mentioned, it would also be possible to make the base piece 1 integral with the cover part 4a of the collapsible tube 3.

The described closures are not only suitable for collapsible tubes but also for bottles, cans, oilers, etc.

I claim:

1. A container closure comprising a base member having an inner and an outer surface, a passage extending from said inner surface into said base member and having a blind end adjacent said outer surface, an integral plug formed on said outer surface in alignment with said passage, said blind end, plug and outer surface defining a disruptable portion between said blind end and outer surface encircling said plug to permit removal thereof, a shutter slidably overlying said outer surface of said base member, an opening in said shutter, cooperating guiding surfaces on said base member and shutter defining a path for displacement of each point of said shutter relative to said base member, said plug of the base member extending outwardly through said opening in said shutter thereby preventing displacement of the shutter relative to the base member, and a cap slidably overlying said shutter and retained and guided on said base member for rotation about an axis aligned with said axial passage and plug, said cap having an axial opening through which said plug extends outwardly, said shutter and cap having interengaging formations coupling said shutter to said cap for displacement of said shutter on said base member along the said cooperating guiding surfaces thereof on rotation of said cap about said axis after removal of said plug.

2. A container closure comprising a base member having an inner and a spheric outer surface, an axial passage extending from said inner surface into said base member and having a blind end adjacent said spheric

outer surface, an integral plug formed on said spheric outer surface in axial alignment with said passage, said blind end, plug and outer surface defining a disruptable annular portion of said base member between said blind end and outer surface encircling said plug to permit removal thereof, a calotte-shaped shutter slidably overlying said spheric outer surface of said base member and guided thereon for rotation about an axis which intersects the axis of said axial passage and plug at the center of said spheric outer surface, said shutter having an opening in alignment with said axial passage of the base member and through which said plug thereof extends whereby said shutter is prevented from rotation, and a cap slidably overlying said shutter and retained and guided on said base member for rotation about the axis of said axial passage and plug, said cap having an axial opening through which said plug extends outwardly, said shutter and cap having inter-engaging formations coupling them for joint rotation thereof about their respective axes after removal of said plug.

3. A container closure as claimed in claim 2 in which said calotte-shaped shutter has a spheric inner surface and a spheric outer surface having the same center as said spheric inner surface, and a plane marginal surface, said base member has a plane annular shoulder encircling its said spheric outer surface, and said cap has a spheric inner surface, said spheric inner surface of the cap fitting the spheric outer surface of the shutter, the spheric inner surface of the shutter fitting the spheric outer surface of the base member, and the marginal surface of the shutter slidably abutting the annular shoulder of the base member whereby said shutter is guided for rotation on said base member, said interengaging formations of the shutter and cap being provided on the spheric outer surface of the shutter and on the spheric inner surface of the cap, respectively, and comprising a lug in the shape of a body of revolution projecting above one of these surfaces with its axis directed towards said center, and a groove in the other of these surfaces in a radial plane thereof with respect to the axis of rotation of that one of the shutter or cap to which said other surface belongs, said lug being engaged in said groove.
